BOOK HOLDER AND PROTECTOR

John B. Farrior, Jr., Washington, D. C.

Application April 11, 1939, Serial No. 267,275

4 Claims. (Cl. 281—19)

The present invention relates to a book holder and protector and more particularly to a device of this character which is especially adapted for use in connection with sales books and the like.

One of the objects of the present invention is to provide in combination with a sales book a novelly constructed holder and protector therefor.

10 Another important object of the invention will be found to reside in the novel means in combination with the protector and holder for firmly and removably securing the sales book or pad within the holder.

15 Other objects of the invention including durability, simplicity of construction and low cost of manufacture thereof, will become apparent from a study of the following description when considered in connection with the drawings 20 wherein like characters denote like or corresponding parts throughout the several views, and in which:

Figure 1 is a perspective view of the book protector and holder showing a sales book secured 25 therein,

Figure 2 is a fragmentary perspective view of the device illustrated in Figure 1 showing the cover in open position and the manner in which the back portion of the book is securely and 30 movably held in the device,

Figure 3 is a vertically sectional view of Figure 1 taken on line 3—3 thereof,

Figure 4 is a fragmentary perspective view of a modified form of the invention,

35 Figure 5 is a fragmentary vertical sectional view of Figure 4 taken on line 5—5 thereof looking in the direction of the arrows,

Figure 6 is a fragmentary perspective view of a modified form of holding means for securing 40 the book in position in the holder,

Figure 7 is a perspective view of a further modified form of the invention showing the compartment for storing the used leaves of the sales book therein,

45 Figure 8 is a longitudinal vertical sectional view of Figure 7, and

Figure 9 is a vertical sectional view of Figure 8 taken on line 9—9 thereof looking in the direction of the arrows.

50 In the accompanying drawings wherein for the purpose of illustration is shown preferred embodiments of the invention, and referring more particularly to Figures 1 to 3 inclusive, the reference numeral 12 clearly designates the bottom portion of the book cover and protector,

which is of rectangular shape, and bent upwardly at one end at right angles thereto defining the front end portion 14 of the holder. A top 16 which includes a substantially rectangular shaped cover plate 18 having one end bent downwardly 5 at right angles is pivotally mounted to the bottom portion 12 at 20. It will be observed that the free end of the cover 16 terminates short of the upstanding front portion 14 substantially covering and protecting the top of the sales pad. 10 Thus, it will be observed that the protector, or holder as previously described forms a substantially box-like structure in which, the sales pad or book 22 is secured. The sales pad 22 is provided with a substantially flexible cardboard 15 back 24, as illustrated in Figure 3, the free end of which is slid under the integral inwardly directed tongues 26 adjacent the pivoted end of the holder. As clearly illustrated in Figures 2 and 3 the back 12 adjacent the pivoted end is 20 provided with integral inwardly directed tongues 26 which are disposed in spaced relation to the upper side of the back 12 for receiving the free end of the back of the book as illustrated in Figure 3. A holder 28 is bent around the back 12 25 having inwardly directed tongues 30 in spaced relation to the upper portion of the bottom 12 and is freely slidable on the back. It will thus be observed that the back of the sales pad or book is inserted through the slidable holder and beneath the tongues 26 and upon a forward sliding of the holder 28 the book is firmly secured to the back 12. The size of the holder is such, that the upstanding forward end 14 is in abutment with the forward end of the sales pad. 30

35 Referring now to Figures 4 to 6, inclusive, it will be observed that there is illustrated a further modified form of the invention in which, the back 34 is of general rectangular shape and is provided with an upstanding front side 36 which is 40 bent upon itself in substantially oval shape forming an abutment for the forward end of the sales pad. In this form of the invention, as illustrated in Figures 4 and 5, the inwardly directed tongues 38 at their outermost ends are 45 bent downwardly as at 39 into contacting relationship with the upper portion of the back 34 forming an abutment or a stop for the free end of the back of the sales pad. In this form of the invention there is also provided a holder 40 50 which is slidable on the back and upon a sliding of the holder 40 in position adjacent the tongues 38, the back of the pad is inserted between the holder 40 and the back and underneath the tongues 38 whereupon a forward sliding of the 55

holder 40 toward the forward end of the sales pad securely holds the pad in position in the holder with the forward end of the pad in abutment with the forward circular end 36 of the back. If so desired, as illustrated in Figure 6, the tongues 44 may as distinguished from being turned downwardly at its free outer end into abutting contact with the upper portion of the back 34 be entirely spaced therefrom permitting of the free slidable engagement of the back of the pad therebetween.

Attention is now directed to Figures 7 to 9, inclusive, wherein, the cover 48 which is pivotally mounted as previously described to the back 50 which has an upstanding front end portion 52 is provided with a sales slip receiving compartment 54. As illustrated in Figure 7 this compartment is formed by bending the sides of the top 48 downwardly and inwardly until the free ends substantially meet as at 56 defining a substantially box-like compartment. The free end of the top 48 is bent downwardly as at 58 terminating short of the inturned bottom portion of the compartment defining an opening 60 through which the used sales slip may be inserted for holding the same within the compartment. It must be observed in this connection that the length and size of the compartment is such as to freely and slidably receive the used sales slips. In this form of the invention as illustrated in Figure 7 there is associated with the book 50, tongues 51 and a slidable keeper 53 for securing the sales book within the holder as disclosed with respect to Figures 1 to 3 inclusive.

It will thus be seen, that there is provided, a novelly constructed sales book or pad protector and holder which provides for the firm holding and removal of a sales book therein protecting the sales book at all times. There is also provided novelly constructed compartment means in combination with the book for temporarily holding the used sales slips until the same are subsequently filed away.

While there are shown for the purpose of illustration several preferred embodiments of the invention it is to be understood that the invention is capable of various changes and further modifications without departing from the spirit and scope thereof and it is intended therefore, that only such limitations shall be imposed thereon as are necessitated by the prior art or by the scope in the claims.

What I claim is:

1. A sales book holder and protector comprising, a bottom having one end turned upwardly, a cover pivoted to the other end of said bottom,

tongues secured to the sides of said bottom and being bent inwardly in spaced relationship to the upper side of said bottom for receiving the free end of the back of a sales pad, and a rectangular shaped holder longitudinally slidable of said bottom through which the back of the sales book is inserted for cooperation with the bottom for securing said sales book to the bottom thereof. 5

2. A sales book holder and protector comprising a bottom having one end turned upwardly at 10 right angles thereto, a cover having one end turned downwardly and pivoted to the other end of said bottom, tongues secured to the sides of said bottom adjacent the pivoted end and being bent inwardly in spaced relationship to the upper 15 side of said bottom for receiving the free end of the back of a sales book, and a rectangular shaped keeper slidable longitudinally of said bottom through which the back of the sales book is inserted for cooperation with the bottom of the 20 holder for securing said sales book to the bottom thereof.

3. A sales book holder and protector comprising a bottom having one end turned upwardly at a right angle thereto, a cover having one end 25 turned downwardly and pivotally connected to the other end of the bottom, said bottom having tongues integral with the sides and bent inwardly in spaced relationship to the top portion of said bottom adjacent the pivoted end thereof for slidably receiving the free end of a back of a sales book, the outermost sides of said tongues being bent downwardly in contacting relationship with the upper portion of the bottom for defining an abutment for the free end of the back of the sales 35 book, and a keeper longitudinally slidable of the bottom through which the back of a sales book is inserted for securing the upper portion of the back of a sales book adjacent the bottom.

4. A sales book holder and protector comprising a bottom having one end turned upwardly and being bent inwardly upon itself defining in cross section a substantially oval shaped abutting end portion, a cover having one end turned downwardly and pivotally connected to the other end 45 of said bottom, integral tongues on the opposed sides of said bottom adjacent the pivoted end being bent inwardly upon the upper portion of the bottom in spaced relationship thereto for receiving the free end of the back of a sales book, and a keeper longitudinally slidable of the bottom through which the back of a sales book is inserted for securing the same in position on the upper portion of the bottom. 50

JOHN B. FARRIOR, JR.
